UNITED STATES PATENT OFFICE.

THEODORE L. VALERIUS AND OLAF LARSEN, OF FORT ATKINSON, WISCONSIN,
ASSIGNORS TO THE CREAMERY PACKAGE MANUFACTURING COMPANY, OF
CHICAGO, ILLINOIS, A CORPORATION OF ILLINOIS.

BOTTLE FILLING AND CAPPING MEANS.

1,289,973.

Specification of Letters Patent.

Patented Dec. 31, 1918.

Original application filed July 10, 1914, Serial No. 850,123. Divided and this application filed January 15, 1918. Serial No. 211,922.

To all whom it may concern:

Be it known that we, THEODORE L. VALERIUS and OLAF LARSEN, citizens of the United States, residing at Fort Atkinson, in the county of Jefferson and State of Wisconsin, have invented certain new and useful Improvements in Bottle Filling and Capping Means, of which the following is a specification.

10 This invention relates to machines for filling and capping bottles, particularly such bottles as are used for milk and cream, the invention being particularly applicable to machines for filling and capping cased bottles; and this application is a division of our copending application Serial No. 850,123, filed July 10, 1914.

Generally stated, the object of the invention is to simplify the construction of machines in this class. This object is attained in part by using capping devices as well as filling devices which have no operative connection with the driving mechanism and which are actuated simply by the operation 25 of pressing the bottles against the capping devices. The means for forwarding the bottle cases also has been simplified. The mechanisms are so arranged that it is not necessary to alternately start and suspend 30 their operation, but on the contrary the machine may be run continuously, cases of empty bottles being placed upon the machine at the convenience of the operator.

Other advantages and improvements will 35 be apparent from an examination of the description and drawings, in which latter Figure 1 is a top plan view of a machine embodying the features of our invention. Fig. 2 is a view taken approximately in the plane of 40 dotted line 2—2 of Fig. 1. Fig. 2^a is a view of one of the cappers, showing a bottle in operative relation thereto. Fig. 2^b illustrates a means for detachably securing each capper in place. Fig. 2^c is a fragmental 45 view illustrating the means for supporting the cappers. Fig. 3 is a view of the front end of the machine, the lower portion being sectioned in the plane of dotted line 3—3 of Fig. 2. Fig. 4 is a top plan view of the elevator and its guiding means. Fig. 5 is a fragmental side elevation showing the driving means. Fig. 6 is a horizontal sectional view taken in the plane of dotted line 6—6

of Fig. 2. Fig. 7 is a fragmental view showing the forwarding mechanism, the view being taken in the plane of dotted line 7—7 of Fig. 6. Fig. 8 is an elevation partly in section illustrating one of the cappers. Fig. 9 is a longitudinal section of the capper in association with a bottle. Fig. 10 is a transverse section on line 10 of Fig. 8, and Figs. 11 and 12 are transverse sections on line 11 of Fig. 9 and line 12 of Fig. 8, respectively.

The embodiment herein shown of our invention comprises two standards or side frames 1 and 2 rigidly secured together in any suitable manner. Upon these standards are supported a stationary tank 3 for the liquid with which the bottles are to be filled, and a stationary plate 4 which supports the cappers. The tank 3 is provided with filling valves 5 of any suitable or well-known character, said valves being arranged in position to register with the bottles contained within a bottle case. Herein the valves 5 are shown as arranged to fill a case of twelve quart bottles, but it will be understood that the valves might be arranged to fill pint bottles, of which there are usually twenty in a case. The valves 5 are preferably arranged in two groups, there being one dozen valves in each group. The groups of filling valves are arranged along the machine in position to operate successively. The first group of filling valves fills the bottles in a given case partially full. The second group of valves completes the filling of the bottles. An advantage of thus filling the bottles in two steps is that the foam caused by the initial part of the filling is allowed to subside before the filling is completed.

The cappers are so constructed that they are operable simply by engagement of the bottle therewith. In order to provide the space required for the cappers, they are divided into two groups of six cappers each, the cappers of each group in the present instance being arranged in staggered relation to each other. The first group is positioned so as to cap half of the bottles in a case, some in each row, while the second group caps the remaining bottles in the case.

The bottle cases are moved along beneath the groups of filling valves and cappers, and are periodically raised to place the bottles in operative relation to the valves and cap-

pers. The end of the machine at which the bottle cases are introduced (*i. e.*, the right hand end in Fig. 2) will be herein-after termed the front end of the machine.

5 The cappers, which are of the type disclosed in applicants' prior Patent No. 1,139,931, dated May 18, 1915, are unitary in their character, being structurally independent of each other, and are detachably 10 mounted upon the supporting plate 4 so as to be individually removable. The cappers are arranged to be operated solely by engagement of the bottles therewith. The construction and mounting of the cappers 15 may be described as follows:

Each capper comprises a tubular body 6 having a bell-mouth 7 and a cap magazine 8, the magazine being alined with and rigidly secured to the body in any suitable way. 20 The magazine extends slidably through an opening in the capper-supporting plate 4. 9 is a cam fixed to a collar 15 and arranged to actuate a cap-ejecting slide 9^a which is reciprocable transversely in the body and 25 is arranged to singly and successively eject the lowermost cap in the magazine. The ejected cap falls onto an exteriorly-positioned curved guide 9^b which is pivoted at its upper end and by which the cap is directed into position to be depressed into the 30 bottle by a cap-seating punch 10 slideable in the body 6, the guide 9^b being swung to one side by the plunger as the latter descends. The punch 10 is supported from the 35 plate 4 by means of two rods 11, the upper ends of which extend slidably through openings in the plate 4. Above said plate the rods are provided with an annular groove to fit the narrow portion of a key-hole slot 40 12 in a washer 13. Said washer lies upon the plate 4 and is held against rotation by means of a lock pin 14 fixed in the plate 4 and passing freely through the wide portion 45 of one of the slots 12. The cam 9 is supported by a ring 15 in which the magazine 8 is freely slideable. The ring 15 bears against shoulders 11^a formed on the rods 11 by enlarging the diameter of the same. Coiled springs 16 are interposed between 50 the plate 4 and the ring 15, said springs normally holding the cap-seating punch 10 and the ring 15 in the position shown in Figs. 2 and 8. The lower ends of the rods 11 are connected to a cross rod 10^a entered 55 through the punch 10 (Fig. 12) with its opposite ends protruding through vertical slots 6^a in the body 6, which slots permit relative longitudinal movement of the punch and body. When the parts are in their 60 normal or inoperative position, the body 6 and magazine 8 thereon are supported by the ends of the rod 10^a bearing in the upper ends of the slots 6^a. When a bottle is pressed against the bell-mouth 7, the body 6 and the magazine 8 rise until the bottle

strikes the cap-seating punch 10, a cap having previously been fed into position between the bottle and the punch. When the cap is fully seated, the upper end of the body 6 strikes the ring 15. Continuing 70 upward movement of the bottle causes the ring 15 to rise, thus relieving the punch 10 of the pressure of the springs 16 and permitting the punch to rise with the bottle. When the bottle is lowered, the body 6 and 75 the magazine 8 descend by gravity to their normal position.

The bottle cases are supported beneath the filling valves and the cappers upon two parallel slide rails 17, the forward and rear 80 portions of said rails being rigidly secured together by means of two cross pieces 18. Secured to the ends of the cross pieces 18 below the rails 17 are two bars 19 (Fig. 7). It will be seen that the rails 17, cross pieces 85 18 and bars 19 form a rigid frame. Said frame is supported for reciprocation upon rollers 20, said rollers being carried by a drip pan or trough 21 which is rigidly secured to the standards 1 and 2. This drip pan is of open rectangular shape through the central opening of which the elevating means to be later described operates. The bars 19 extend through guideways 22 (Figs. 9 and 7) formed in the side edges of the 95 trough 21. To the forward end of each of the rails 17 is secured a support 23 in which rollers 24 are journaled. Fixed to the rails 17 are spacer blocks 25 for the purpose of spacing the bottle cases the proper distance 100 apart so that the bottles therein shall register with the filling valves and the cappers. The rear ends of the roller supports 23 serve as stops to position the last case. 26 are stationary case guides (see Fig. 2) and 27 105 are stationary rail guards (see Figs. 1, 6 and 7).

The rails 17 are moved toward the rear end of the machine to advance the cases by means of a cam 28 (see Fig. 2) fixed upon a 110 shaft 29, said shaft being rotatably mounted in the standards 1 and 2. The cam 28 operates upon a roller 30 carried by a fork 31 which is rigidly connected to a sleeve 32, said sleeve being mounted upon a shaft 33. Rigid with the sleeve 32 are two arms 34 which are connected by means of links 35 to brackets 36 fixed to the bars 19. The roller 30 is held against the periphery of the cam 28 by means of a weight 37 attached to a cable 38, said cable being secured to the forward bracket 115 38 and running over a guide sheave 39. It will be seen that as the shaft 29 is rotated, the rails 17 will be reciprocated.

After each rearward movement of the rails 17, the four bottle cases that are directly beneath the filling valves and the cappers are lifted off the rails to place the bottles in operative relation to the filling valves and the cappers, by means of an elevator 120 40 125

(see Figs. 2 and 6), said elevator being provided at opposite sides with guides 41 which are mounted for vertical movement in guideways 42 formed upon the inner sides of the standards 1 and 2. Upon the top of the elevator 40 is a table 43 (see Figs. 3 and 6). On the upper side of the table 43 are four sets of ribs 44 (Fig. 6), each set of ribs being adapted to extend into a bottle case far enough to bear against and thus support the wires or other elements that constitute the bottom of the case when the case is elevated. When the bottles are pressed against the filling valves and the cappers, the pressure of the bottles upon the wires is borne by the ribs 44, thus obviating injurious stress upon the wires.

The elevator 40 is raised by means of the cam 28 (see Fig. 2), said cam operating against a roller 45 which is located at the pivotal joint of the toggle arms 46. The lower toggle arm is pivoted at 47, the upper toggle arm being pivoted to the elevator 40 at 48.

25 To one end of the shaft 29 is fixed a spur gear wheel 49 (Fig. 1) that meshes with a pinion 50. The pinion 50 is rotatably mounted upon a stud shaft 51 on the standard 1. The pinion is rigidly fixed to a change gear wheel 52 that meshes with a pinion 53, the latter being rigidly mounted upon a shaft 54. One end of the shaft 54 carries a drive pulley 55.

A platform 56 is secured to and extends 35 between the forward end of the rail guards 27. Said platform is located just above the plane of the rails 17, so that the rails may extend beneath the platform when the rails move forward.

40 Assuming the parts to be in the position shown in Fig. 2, the operation is as follows: The cam 28 actuates the elevator 40 to raise the four bottle cases and hold them elevated for a time. The operator places a case of 45 empty bottles on the rollers 24. As the roller 30 runs off the dwell 28^a the weight 37 draws the rails 17 forward (to the right). The case which the operator placed upon the rollers 24 is prevented from being carried 50 to the right, as the rear edge of the platform 56 acts as a stop to detain the case; consequently as the rollers 24 pass under the platform 56 said bottle case is pushed off the rollers onto the rails 17 between the rear 55 ends of the supports 23 and the adjacent pair of spacer blocks 25. As the roller 45 runs off the dwell 28^a, the elevator descends, depositing the bottle cases on the rails 17. As the roller 30 runs off the dwell 28^b, the rails 60 17 move rearwardly, thereby advancing the cases so that the bottle case last placed upon the rails is beneath the first group of filling valves. The elevator then lifts four of the cases leaving the fifth case containing filled 65 and capped bottles standing on the rails. If

the case containing filled and capped bottles is not lifted off the rails 17 by a workman before the rails again move toward the front, said case is carried against the case that is in operative relation to the second group of 70 cappers, and is thereby detained as the rails move to the front.

It will be seen that the filling devices and cappers are actuated solely by the operation of lifting the bottles into contact with said valves and cappers. The only power-driven mechanisms of the machine are the elevator and the case forwarding rails. No bottle cases are in transit while bottles are being filled and capped, hence there is no danger 75 of interference between the cases, and no necessity of providing safety devices to prevent such interference. By reason of these factors it has been possible to reduce the mechanism of the machine to a minimum, with a corresponding saving in cost and increased ease of operation.

80 It will be understood that the invention is not limited to the use of any particular number of filling valves and cappers, arranged in any particular manner, but that one or more bottles may be passed through the machine and each successively acted upon by two filling valves and one capper. 85 In the following claims, the word "group" 90 is intended to mean two or more.

We claim as our invention:

1. A bottle filling and capping machine having, in combination, devices for operating upon bottles each operable solely by the engagement of a bottle therewith, a horizontally reciprocatory bottle support operable to move a plurality of bottles into position beneath said devices, an elevator, and means for coöperatively actuating the elevator and the support whereby to raise said bottles into engagement with said devices and to lower them to the support in an advanced position relative thereto.

100 2. In a cased bottle filler and capper, the combination of two groups of filling valves, each group containing as many valves as there are bottles in a case, two groups of cappers, each group containing half as many cappers as there are bottles in a case, the cappers of the first group being adapted to cap certain of the bottles in a given case, and the cappers of the second group being adapted to cap the remaining bottles in a given case, means for simultaneously lifting four 110 cases into operative relation with the filling valves and cappers and for lowering said cases, and means operatively associated with the lifting means for forwarding said cases step by step past the series of filling valves 115 and cappers.

120 3. In a machine for filling bottles and applying caps thereto, a plurality of automatically operable filling valves and cappers, a horizontally reciprocatory bottle 130

support operable to move a plurality of bottles into position beneath said devices, an elevator, and means for coöperatively actuating the elevator and the support whereby to raise said bottles into engagement with said filling and capping devices and to lower them to the support in an advanced position relative thereto.

4. In a machine for filling bottles and applying caps thereto a plurality of filling valves and one or more cappers each operable solely by the engagement of a bottle therewith, a horizontally reciprocatory bottle support operable to move a plurality of bottles into position beneath said devices, an elevator, and means for coöperatively actuating the elevator and the support whereby to raise said bottles into engagement with said filling and capping devices and to lower them to the support in an advanced position relative thereto, there being half as many cappers as filling valves.

5. In a machine for filling bottles and applying caps thereto, filling devices, capping devices comprising cap feeding and applying means, means for moving a plurality of bottles in a horizontal plane beneath said devices, and means for simultaneously lifting a bottle into engagement with each of said filling and capping devices, said filling and capping devices being operable solely by the engagement of the bottles therewith.

6. A bottle filling and capping machine having, in combination, filling and capping devices, each operable solely by the engagement of a bottle therewith, a pair of spaced supporting rails slidably mounted beneath said devices and arranged to support a plurality of bottle cases in spaced relation, an

elevator, and means for coöperatively actuating the elevator and support whereby to raise said cases to carry the bottles into engagement with said filling and capping devices and to lower them to the rails in an advanced position relative thereto.

7. In combination, an elevator, means for actuating the elevator, means above the elevator for operating on bottles carried by the elevator, case-moving members below said operating means, a platform at one end of the machine frame, means for reciprocating said case-moving members to move said members beneath said platform and withdraw said members therefrom, the portions of said members adjacent to the platform being adapted to support a bottle case, and said platform acting as a stop to detain the case from movement to shift its position from the case-moving members when they move toward the platform.

8. A machine for operating upon bottles having, in combination, a plurality of filling valves and one or more capping devices, there being half as many capping devices as filling valves, an elevator, horizontally reciprocatory means for advancing a bottle step by step from a position beneath one filling valve to a position beneath the next and from the last filling valve to a position beneath the capping device, each filling valve and capping device being operable solely by the engagement of a bottle therewith, and means for coöperatively actuating said bottle advancing means and said elevator.

In testimony whereof we have hereunto set our hands.

THEODORE L. VALERIUS.
OLAF LARSEN.
